UNITED STATES PATENT OFFICE.

JOHN W. McBRINE, OF MEDFORD, MASSACHUSETTS.

MOUTHPIECE ATTACHMENT FOR TELEPHONES.

No. 902,896.

Specification of Letters Patent.

Patented Nov. 3, 1908.

Application filed June 17, 1907. Serial No. 379,351.

To all whom it may concern:

Be it known that I, JOHN W. McBRINE, of Medford, in the county of Middlesex and State of Massachusetts, a citizen of the United States, have invented a new and useful Improvement in Mouthpiece Attachments for Telephones, of which the following is a full, clear, and exact description, reference being had to the accompanying drawings, forming a part of this specification, in explaining its nature.

The importance of covering the mouthpiece of a telephone in such manner as to prevent the entrance into it of exhalations from the breath, saliva and other matter has already been recognized and various attachments or devices have been used for the purpose of securing such covering. These devices are mainly adapted to cover the mouthpiece with a specially formed disk of treated or antiseptized paper. It would seem, however, that for the purpose of keeping foreign matter out of the mouthpiece any piece of common thin paper might do. I have accordingly provided by my invention a simple and inexpensive attachment or device consisting of two members between which a piece of common thin paper may first be clamped and afterward be applied so as to cover the end of the mouthpiece.

The improved attachment or device may best be seen and its adaptability understood by reference to the drawings in which—

Figure 1 shows the attachment in front elevation as applied to the mouthpiece of a telephone. Fig. 2 shows a cross section of the same when so applied. Fig. 3 shows in enlarged detail a special feature of construction to which reference will hereinafter be made. Fig. 4 shows in side elevation the members or elements of the attachment separate from one another. Fig. 5 shows the separate members in slight modification. Fig. 6 shows an enlargement of a portion of the same to which reference will hereinafter be made.

Referring to the drawings:—A represents the attachment or device and B the conventional form of telephone mouthpiece to which the attachment is adapted to be applied.

The attachment as shown comprises two members or elements a and a' made preferably of hard rubber or celluloid. They are so adapted to one another that when combined a piece of paper C may be held clamped

between them after which the paper may be applied to cover the end of the mouthpiece by the member a of the attachment combining therewith, as will hereinafter be explained. Moreover, it is to be noted that any common piece of thin paper of sufficient size will do, the attachment being specially adapted to receive the paper between its members and apply it to cover the mouthpiece.

With respect now to the more specific details of construction. The member a of the attachment is in the nature of an annular ring or collar made in part of a size to fit over the mouthpiece and become attached thereto. First however, with respect to the relationship of the member a to its complementary member a' and the mode of securing the paper C between the members, it is to be noted that the member a consists in part of an annular neck portion a^2 on which the member a' is adapted to fit in the manner of a cover. In fact the member a' is a clamp consisting of an annular rim a^3 and a top portion a^4 in which there is a large hole or opening. The members a and a' , being thus formed, are adapted to receive a piece of thin paper between them, which is placed over the end of the neck portion of the member a , then when the members are combined the paper between them will be drawn taut in over the hole or opening in the member a' completely closing said opening, or in other words, the combined members will be provided with a diaphragm of thin vibratory material through which the sound waves will readily pass. The clamp member a' is made, of course, to fit rather tight over the neck a^2 which receives it so that even with the paper interposed the parts may be held tightly together. In order, however, that there may be some bearing stress to hold the members in combination and the paper in place, I prefer to provide the neck with slits a^5 properly spaced from one another in order that the interposing members forming the neck may give slightly when the clamp member a' is put on and afterward by their out pressing tension or stress may hold it and the paper in place. It is also to be observed that the member a at the forward end of its neck turns abruptly outward by an annular edge a^6 which forms the annular bead a^7 , the capability of which will hereinafter be referred to. As for the outwardly turned annular edge a^6 , it acts as a shoulder against which the rim of

the clamp member a^1 is adapted to bear when the members are in proper conjunction, or in other words, when the clamp member has been compressed so far that the end of the neck will engage on the inside with the top a^4 of the clamp member. The special advantage of this is that the paper will be bent in opposite directions, which I have found is especially useful in keeping the members in proper conjunction.

With reference now to the means for securing the members or attachment to the end of the mouthpiece. As will be noted, the mouthpiece of a telephone is bell-shaped in form, turning or flaring outwardly, forming upon its end an annular rim or edge b . It is to this edge of the mouthpiece that I adapt my attachment to be secured. For this purpose the member a in its part or portion a^8 , forward of its annular neck a^2 and the outward turned annular edge a^6 forming the bead a^7 as aforesaid, is made slightly smaller than the end of the mouthpiece over which it is adapted to extend, while between this part and the neck the bead a^7 forms on its inside an annular socket a^9 into which the rim or edge b of the mouthpiece is adapted to fit and, when so contained, to bear against the inside of the annular edge a^6 as a stop. In order that the rim or edge b may easily slip or spring into and out of the socket a^9 , the contracted portion a^8 of the member a is provided with one or more slits a^{10} , so enabling it to give slightly. Of course these slits may extend across the bead as shown in the drawing, if it is desirable. By this means it is evident that the attachment is not only secured or removed from the end of the mouthpiece, but when secured it is held tightly clamped and locked in place, the sharp rim or edge of the mouthpiece being utilized for this purpose. It will also fit should there be any slight variations in the sizes of the mouthpieces of different telephones.

In Figs. 5 and 6 I have shown a slight variation in the construction of the mouthpiece in that the neck a^{11} of the member a is made slightly beveled. The clamp member a^1 is similarly beveled on the inside portion of its rim a^{12} , so that when the members are combined they will hug the paper with a gradually increasing degree of tightness or pressure. I have also shown the clamp member a^1 provided with a locking edge a^{13} which, when the members are combined is adapted to slip over the annular bead a^7 of the member a , so holding the clamp member locked in place. In order that this may easily be accomplished I provide this locking edge with one or more slits a^{14} , so enabling the parts to give slightly or sufficiently for the purpose specified.

The attachment is very simple and inexpensive. A piece of paper can quickly and easily be clamped between its members and

then by simple pressure applied to cover the end of the mouthpiece. I would also call attention to the fact that not only is the paper tightly bound between the members, but they in turn are tightly fixed to the mouthpiece so that the paper practically becomes a vibratory part of the mouthpiece and does not interfere with the normal working of the telephone.

While I have used the term paper as being the best material known to me for covering the end of the mouthpiece and for illustrating the especial capability of my device, I mean, of course, any suitable material which would form a proper diaphragm when clamped between the members of the attachment.

Having thus fully described my invention, I claim and desire to secure by Letters Patent of the United States:—

1. An attachment or device of the character specified for the mouthpiece of a telephone having separate members attachable one to the other independently of said mouthpiece and adapted when combined to bind and hold a diaphragm between them, and means whereby said combined members may be attached to said mouthpiece of the telephone and said diaphragm be applied thereto.

2. An attachment or device of the character specified for the mouthpiece of a telephone having separate members attachable one to the other independently of said mouthpiece, a diaphragm held bound by and between said members when combined, and means whereby said combined members may be attached to said mouthpiece of the telephone and said diaphragm applied thereto.

3. An attachment or device of the character specified for the mouthpiece of a telephone having separate members adapted to conjoin or combine with one another for holding a flexible diaphragm between them and during the combination of said members to stretch said diaphragm, and means whereby said combined members may be attached to said mouthpiece of the telephone and said diaphragm be applied thereto.

4. An attachment or device of the character specified for the mouthpiece of a telephone having separate members one of which members is provided with an edge over which said other member is adapted to draw for stretching and holding a diaphragm between said members, and means whereby said members may be attached to said mouthpiece of the telephone and said diaphragm be applied thereto.

5. An attachment or device of the character specified for the mouthpiece of a telephone having separate members attachable one to the other independently of said mouthpiece and adapted when combined to hold a diaphragm between them, and a

socket formed within one of said members into which the edge or rim of said mouthpiece is adapted to fit whereby said combined members may become attached to 5 said mouthpiece and the diaphragm be applied thereto.

6. An attachment or device of the character specified for the mouthpiece of a telephone, having separate members one of 10 which, a clamp member, is adapted to conjoin with the other of said members and hold a diaphragm tight over the end thereof, and which other member in part is adapted to fit over the projecting edge or rim of said 15 mouthpiece by a yielding socket formed in the said part of the member in which said edge or rim is adapted to be contained.

7. An attachment or device of the character specified for the mouthpiece of a telephone having separate self-combining members which when combined are adapted to hold a diaphragm between them independently of said mouthpiece and one of which members is formed whereby said member is 20 self-attaching to said mouthpiece of the telephone for applying said combined members and the diaphragm thereto.

8. An attachment or device of the character specified for the mouthpiece of a telephone, having separate members one of 30 which, a clamp member, is adapted to conjoin with the other of said members and hold a diaphragm tight over the end thereof, means whereby said members may be held 35 under tensional pressure in conjunction with one another, and means whereby they may be held in frictional engagement with the end of said mouthpiece and said diaphragm be applied to cover the end thereof.

40 9. An attachment or device of the character specified for the mouthpiece of a tele-

phone having separate members one of which, a clamp member, is adapted to conjoin with the other of said members and hold a diaphragm tight over the end thereof, 45 means whereby said members may be held in self-locking conjunction with one another, and means whereby said other member may be self-locked to the end of the mouthpiece of the telephone and said diaphragm be applied to cover the end thereof.

10. An attachment or device of the character specified for the mouthpiece of a telephone, the same having separate members one of which, a clamp member, is adapted to 55 conjoin with said other member and hold a diaphragm bound tight over the end thereof, means whereby said members may be conjoined with a gradually increasing pressure, and means whereby said other member may 60 attach itself to the said mouthpiece and said diaphragm be applied to cover the open end thereof.

11. An attachment or device of the character specified for the mouthpiece of a telephone, having separate members one of which, a clamp member, is adapted to conjoin with said other member and hold a diaphragm bound tight over the end thereof, a bead on said other member forming a socket 70 on the inside thereof in which the edge or rim of said mouthpiece is adapted to fit, whereby said member or attachment may become attached to the mouthpiece of the telephone and the diaphragm be applied to cover the 75 end thereof, and a locking edge on said clamp member adapted to fit over said bead when the members are in conjunction.

JOHN W. McBRINE.
